UNITED STATES PATENT OFFICE.

GEORGE FORSTER, OF PHILADELPHIA, PENNSYLVANIA.

NOTIFYING OR CALL DEVICE FOR TELEPHONES.

Application filed July 24, 1920. Serial No. 398,769.

To all whom it may concern:

Be it known that I, GEORGE FORSTER, a citizen of the United States, residing at Philadelphia, in the county of Philadelphia and State of Pennsylvania, have invented certain new and useful Improvements in Notifying or Call Devices for Telephones, of which the following is a specification.

In various business houses where the telephones are kept in a central office or part of the building set aside for that purpose if a call comes in over the telephone for a person who is not near the telephone, it is necessary for a person to leave the office and inform the party that he or she is desired at the telephone. Very often, due to the rush of business, the party either fails to answer the telephone or does not answer immediately and the receiver remains off the hook of the telephone; thereby interfering with other incoming calls and causing delay of the party at the other end of the wire.

One object of my invention is to provide a device for use in connection with telephones which will be instrumental in causing an alarm when the telephone receiver is taken off its hook in answer to a ring and continue to effect the operation of the alarm until the call has been answered by the proper person. The arrangement of the parts of my invention is such that the alarm can be silenced during the conversation.

Another object is to make the device of my invention of a comparatively simple construction which can be easily and quickly manufactured and which can be attached to a telephone without in any way changing the structure or interfering with the operation of the telephone.

Another object is to make the device of my invention of a durable construction and easy of manipulation.

These objects, and other advantageous ends which will be described hereinafter, I attain in the following manner, reference being had to the accompanying drawings in which

Figure 1 is an elevation showing my invention applied to a telephone under normal conditions when the telephone is not in operation; the receiver hook due to the weight of the receiver thereon serving to cut out the alarm.

Figure 2 is a fragmentary section showing the device in operative position for causing an alarm, and

Figure 3 shows the position of the device during a conversation in which the alarm can be cut out or silenced even though the receiver is off the supporting hook. 60

Referring to the drawing, 4 represents a standard of a telephone of a type in general use; said telephone having a supporting hook 5 for the receiver 6; said receiver due to its weight serving to hold the receiver supporting hook 5 in the position shown in Figure 1. However, it will be noted that upon removal of the receiver 6 the hook 5 will automatically move upward into the position shown in Figures 2 and 3. My improved device includes a housing 7 which may be made of wood or other insulating material and is secured to the standard 4 by any suitable securing means such for example as the clamping band 8. 75

The housing 7 at its top is provided with or includes a cavity 9 having a push button 10 mounted therein; said push button being movable upward by means of a spring 11. In other words the spring 11 serves to move the push button into the position shown in Figure 2. The bottom of the push button has a contact member 12 secured thereto adapted when the push button is moved upwardly by the spring to engage two contacts 13 and 14; said contacts having posts 15 and 16 secured thereto to which the ends of electric wires 17 are respectively attached; said wires leading to an electric generator or battery 17^a and an alarm device such for example as a bell 18; it being noted that when the contact member 12 engages the contacts 13 and 14 that an electric circuit will be completed through the bell 18 causing the ringing of the bell. It will be understood that 95 any other alarm device such for example as a buzzer, a lamp or the like can be substituted for the bell 18. This alarm device 18 may be positioned in any place desired such for example at a location outside of the office or more than one of these devices may be employed. 100

A yoked member 19 is adapted to normally be positioned between the push button 10 and the receiver supporting hook 5. The leg portions 21 of the yoked member extend downwardly at the sides of the housing and have slots 22 through which pass pivot and limiting pins 23; said pins being adapted to be fixed to the housing and serve as a swinging support for the yoked member and also as means for limiting the rising movement 110

of the yoked member. The yoked member has a portion 24 on its head which is bent downwardly to form a cam or finger which when the yoked member is swung into the position shown in Figure 3 will engage the push button and push the latter downward so as to break the circuit. By permitting the finger 24 to remain on the top of the push button and the pins 23 to engage in the lower ends of the slots 22, the contact member 12 will be held down out of engagement with the contacts 13 and 14; thereby breaking the circuit through the alarm device 18. Stop pins 25 may be fixed in the housings 15 at the sides thereof and adapted to be abutted by shoulders 26 on the leg portions of the yoked member 19 to limit the forward swinging movement of the head 20 to a position in which the finger 24 remains on the top 20 of the push button as shown in Figure 3.

Considering that the telephone and my improved device are in the positions shown in Figure 1, if there is a call on the telephone the receiver 6 is lifted from the hook 5 and the hook 5 will then be raised into the position shown in Figure 2. The spring 11 will then raise the push button 10 and the contact member 12 will be moved into engagement with the contacts 13 and 14. This 30 will complete a circuit through the alarm device 18 and as soon as the person who first answers the telephone finds out who is wanted, that person can be notified and the bell will continue ringing until that person 35 answers the telephone. When the person has reached the telephone and starts to answer, the yoked member can be swung from the position shown in Figure 2 to the position shown in Figure 3; thereby causing 40 the push button to be lowered by engagement with the finger 24 and the alarm device will be silenced during the conversation. After the conversation has been completed the receiver is placed upon the hook 5. This operation swings the yoke 19 back due to the engagement of the receiver 6 with the yoke head 20 until the 45 yoke is in its normal upright position as shown in Figure 2 and the weight of the receiver when released will cause the yoked member to be depressed to move the push button downwardly as shown in Figure 1 and thereby break the circuit through the 50 alarm device.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention,

what I claim as new and desire to secure 65 by Letters Patent is:—

1. An attachment for a telephone, including an alarm device located at a position remote from the telephone; means automatically movable to effect the operation of 70 said device and normally held against operation by a part of the telephone necessarily movable in order to answer the telephone, said means being operative when released by said part of the telephone to 75 effect the operation of said alarm device; and means for independently moving said first means into an inoperative position so as to silence said alarm device; substantially as described. 80

2. An attachment, for use in connection with telephones employing a receiver-supporting hook adapted to be held in a normal position due to the weight of the receiver, including an alarm device; a push 85 button; and means interposed between said push button and the receiver-supporting hook of the telephone and adapted when the receiver is on the hook to move said push button into a position to break an electric circuit through said alarm device, said push button, when the receiver-supporting hook is released by the removal of the receiver, being adapted to move into a position 90 to complete an electric circuit through said alarm device, said interposed means having a part adapted to be moved independently of said hook to move said push button into a position to break said electric circuit; substantially as described. 95

3. An attachment, for use in connection with a telephone employing a receiver-supporting hook adapted to be held in a normal position due to the weight of the receiver, including an alarm device located at a position remote from the telephone; a push 105 button adapted to be moved due to the weight of the receiver on said hook to break an electric circuit through said alarm device, said push button, when the receiver-supporting hook is released by the removal of the receiver, being adapted to move into a position to complete an electric circuit through said alarm device; and means operative independently of the receiver to 110 hold the push button in position to break the circuit; substantially as described. 115

4. An attachment, for use in connection with telephones employing a receiver-supporting hook adapted to be held in a normal position due to the weight of the receiver, including an alarm device; a push button adapted to be moved due to the weight of the receiver on said hook to break an electric circuit through said alarm device, said push button, when the receiver-supporting hook is released by the removal of the receiver, being adapted to move into a position 120 to complete an electric circuit through said alarm device; and means operative independently of the receiver to 125 hold the push button in position to break the circuit; substantially as described.

to complete an electric circuit through said alarm device; and means movable independently of said hook and adapted to move and hold said push button in a position to 5 break the circuit through said alarm device; substantially as described.

5. An attachment, for use in connection with telephones employing a receiver-supporting hook adapted to be held in a normal position due to the weight of the receiver, including an alarm device; a push button adapted to be moved due to the weight of the receiver on said hook to break an electric circuit through said alarm device, said push button, when the receiver-supporting hook is released by the removal of the receiver, being adapted to move into a position to complete an electric circuit through said alarm device; a yoked member; and means for supporting said push button and forming a pivotal support for said yoked member, said yoked member having a head adapted to be interposed between the push button and the receiver-supporting hook, said head having a part operative, when the yoked member is swung, to move and hold said push button in a position breaking the electric circuit through said alarm device; substantially as described.

30 6. An attachment for a telephone including an alarm device in a circuit separate from the telephone circuit and located at a position remote from the telephone; means automatically movable to effect the operation of said device and normally held against operation by a part of the telephone necessarily movable in order to answer the telephone, said means being operative when released by said part of the telephone to effect the operation of said alarm device; and means carried by the telephone and movable into position to hold said alarm device inoperative; substantially as described.

45 7. An attachment for a telephone including an alarm device in a circuit separate from the telephone circuit and located at a position remote from the telephone; means automatically movable to effect the operation of said device and normally held against 50 operation by a part of the telephone necessarily movable in order to answer the telephone, said means being operative when released by said part of the telephone to effect the operation of said alarm device; and means carried by the telephone and movable into position to open the circuit to the alarm device when the movable part of the telephone is in the position which it assumes when the telephone is in use; substantially as described.

60 8. An attachment for use in connection with telephones employing a receiver supporting hook adapted to be held in a normal position due to the weight of the receiver, including an alarm device; a switch;

a support for said switch adapted for attachment to the telephone adjacent to the hook; and a pivoted member interposed between the switch and hook and operative to open the switch automatically upon moving 70 the hook to supporting position; substantially as described.

9. An attachment for use in connection with telephones employing a receiver supporting hook adapted to be held in a normal 75 position due to the weight of the receiver, including an alarm device; a switch; a support for said switch adapted for attachment to the telephone adjacent to the hook; and a pivoted member interposed between the 80 switch and hook and adapted to hold the switch open independently of the hook, said member moving to a position to release the switch when the receiver is placed on the hook and to engage the switch to open the 85 same; substantially as described.

10. An attachment for use in connection with telephones employing a receiver supporting hook adapted to be held in a normal position due to the weight of the receiver, 90 including an alarm device; a switch; a support for said switch adapted for attachment to the telephone adjacent to the hook; a pivoted member carried by said support movable between the hook and switch to 95 open the latter when the receiver is supported upon the hook; and means to limit the movement of said member, said member having means to engage the switch when the receiver is removed from the hook to hold 100 the switch open and the alarm device inoperative; substantially as described.

11. An attachment for use in connection with telephones employing a receiver supporting hook adapted to be held in a normal position due to the weight of the receiver, including an alarm device; a switch; a support for said switch adapted for attachment to the telephone adjacent to the hook; a pivoted member carried by said support movable between the hook and switch to 110 open the latter when the receiver is supported upon the hook, said switch, when the hook is released by removal of the receiver, being adapted to move into a position to complete an electric circuit through said alarm device, said alarm device being included in a circuit separate from the telephone; and a projection on said member so that when the latter is moved to one position it will hold the switch open; substantially as described.

In testimony whereof I have signed my name to this specification in the presence of two subscribing witnesses.
